Term of patent 14 years

(Cl. D49—1)

Fig. 1.

Fig. 4

Fig. 2.

Fig. 3.

FIG. 1 is a front perspective view of a dry cleaning machine embodying my new design;

FIG. 2 is a front elevational view thereof;

FIG. 3 is a side elevational view thereof; and

FIG. 4 is a fragmentary vertical cross-sectional view thereof taken on the line IV—IV of FIG. 1.

The side of the dry cleaning machine which is not shown is substantially the same in appearance as the side shown.

The dominant features of my design reside in the portions shown in full lines.

What is claimed is:

The ornamental design for a dry cleaning machine, as shown and described.
